UNITED STATES PATENT OFFICE

JOHN T. WHITEHOUSE, OF CLEVELAND, OHIO, ASSIGNOR TO THE VAN DORN IRON WORKS COMPANY, OF CLEVELAND, OHIO, A CORPORATION OF OHIO

JAIL-DOOR TUMBLER LOCK

Application filed August 13, 1926. Serial No. 128,979.

This invention relates to tumbler locks of a type particularly adapted and intended for use in connection with jail doors.

The requirements peculiar to such a lock are a design to enable the lock to accurately function through a prolonged life of frequent use, and one of such a nature as to obviate the possibility of being manipulated to open or close without possession of the authorized key.

The objects of my invention are therefore to provide such a lock which shall be of ample strength in all its parts, which shall embody numerous means to prevent its manipulation by an instrumentality other than the authorized key, which shall be equally proof against locking or unlocking, and one in which the wear is reduced to the minimum, specifically by utilizing gravity and thereby doing away with all springs in its construction.

The exact nature and advantages of my invention will be apparent from the following description taken in connection with the following drawings in which Fig. 1 is a side view of the lock with cover plate removed to show the parts therein; Fig. 2 is a section along the line 2—2, Fig. 1; Fig. 3 is a section along the line 3—3 Fig. 2; Fig. 4 is a section along the line 4—4, Fig. 1; Fig. 5 is the key corresponding with the lock shown; Fig. 6 is a detail of one of the tumblers employed; Fig. 7 is a detailed view generally similar to that of Fig. 1 showing the bolt and cam arrangement employed for moving the same; Fig. 8 is a section along the line 8—8 of Fig. 7 showing a detail of the cam locking means employed and Fig. 9 is a sectional detail on the line 9—9 of Fig. 1.

The principal parts of the lock are the casing 1 provided with a cover plate, not shown, and adapted to be secured in the usual manner with a jail door; a bolt 2 slidable longitudinally in said casing as is customary; and bolt controlling mechanism to be described, adapted to move the bolt between its respective inner and outer positions flush with and projecting beyond the lock face to posi-

tively secure the bolt in either of these positions, and actuatable by the key 3.

The casing 1 is provided with a circular opening in which is secured by the screws 9 a circular closure plate 5 with a key-receiving aperture 7 adapted to closely fit the bit 11 of the key 3. Mounted for rotational movement in the closure plate concentric with the aperture 7 is a cam member 4, hereinafter referred to merely as a cam, although provided with the hub shown projecting into the closure plate.

The bolt is generally rectangular in section, that portion projecting beyond the casing being solid as is customary, and is provided inside the casing with an opening 8 a portion of which extends through the bolt to accommodate and co-operate with the cam 4; the conformation of the cam and co-acting surfaces *a* and *b* of the bolt opening being as indicated in Fig. 7 and described as follows.

The cam engaging bolt surfaces are generally arcuate the outer arc *a*, (Fig. 7) terminating upwardly in a notch formed by the steps 6—6' from which the inner arc *b* extends downwardly as shown. The arc *a*, corresponds with the cam in the outer or projecting position of the bolt, that of Fig. 1; the arc *b* corresponding similarly with the position of the cam when rotated clockwise 180 degrees from the position shown.

The operation of the cam upon the bolt will be obvious. The cam is adapted for movement by the key through an arc of 180 degrees above the key aperture 7. In the position shown the bolt is positively secured in its outer position by the cam, which occupies longitudinally the cam receiving opening 5 in the bolt. As the cam is moved clockwise, Fig. 7, by means of a key fitting the aperture 7, the bolt is still locked in this position, and hence cannot move until arrival of the cam at substantially an upstanding position, whereupon the cam engages the step 6 of the bolt and slides it inwardly. As the bolt reaches its inner position the arcuate surface *b* of the bolt is concentric with the aperture, whereupon the cam continues downward to an inwardly extending position dur-

ing which time and thereafter the bolt is secured by the cam in its inner position.

To move the bolt outwardly from this position it is necessary to throw the cam back to the position of Fig. 7. During this motion the bolt is locked in inner position until the cam clears the arc *b* (Fig. 7), after which it engages the step 6', moves the bolt to outer position, and as this position is assumed by 10 the bolt, rides down to the position indicated, maintaining the bolt locked in the outer position. The action of the cam to move the bolt however, is subject to a number of other cam and bolt locking means to be described.

15 In the closure plate 5 is embodied a cam locking device as follows: In the cam and closure plate are provided bores vertically aligned and radially extending from the aperture 7 as indicated in Fig. 8. In the closure 20 plate bores are positioned detents 12 slideable therein and urged to engagement with the cam by the springs 13 secured in the closure plate as by the dove-tailed members 31. In the cam bores are corresponding 25 detent release members 14; the balls 15 being provided at the inner bore ends, which are formed to allow the balls to project into the aperture and yet to be retained in the bores.

Operation of the cam lock will be obvious; 30 as the key is withdrawn from the cam aperture, the cam being in a longitudinal position the cam and closure plate bores being in alignment, the detents 12 enter the cam bores as indicated in Fig. 8 to positively lock the cam 35 from any movement. Thereafter to rotate the cam it is necessary that the balls 15 be depressed to a position flush with the inner surface of the aperture 7, to force abutting ends of the detent releases 14 and the detents 40 12 to a position on the periphery of the abutting portions of the cam and closure plate. If the balls are depressed too far to move the detent into the closure plate the cam is locked. In order to depress the balls just 45 sufficiently to free the cam, I form the shank 16 of the key 3 of a size to just fill the aperture, and provide upon the end of the key a conical cam surface adapted to depress the balls as the key is inserted, and which serves 50 as well to facilitate entry of the key into the aperture; the balls during this operation serving as an anti-friction means between the members involved.

Upon the upper and lower portions of the 55 bolt are paired vertically aligned inwardly extending projections 17, 17'. In the bolt opening and secured to the casing as by screws 18 and guide posts 35 is a tumbler frame 19. The tumbler frame is provided 60 with a central open portion, and upon each side with vertically extending slots or ways 20 in each of which is secured as by a rivet 21 extending through blocks 22, a tumbler 23 free for vertical sliding movement. The 65 tumblers are of vertical dimension sufficient

to just clear the projections 17 upon the bolt when properly positioned in their ways. The tumblers are arranged in the tumbler frame in staggered relation with each other as indicated in Figs. 3 and 4 and each is provided with a ward portion 24 extending inwardly of the tumbler frame. The tumbler assembly is so positioned in the casing as to be in longitudinal alignment with the key-receiving aperture 7 so that when the key bit of proper conformation is inserted into the key aperture, the collar 25 abutting the cover plate 5 to longitudinally position the key, and the key is rotated through an arc of 90 degrees, each of the tumblers will be raised 70 to clear the bolt projections, adjacent portions of the key bit engaging the wards of oppositely positioned tumblers. The tumblers however normally project downwards from the tumbler frame to abut the lower 75 projections 17 and 17' of the bolt to prevent movement thereof; and it is evident that if any of the tumblers are raised above the clearing position they will engage the corresponding 80 upper projections of the bolt to equally prevent movement thereof. The tumblers and projections are longitudinally arranged in the casing so that the tumblers will abut the projections in either inner or outer position of the bolt, whereby the bolt is equally 85 secured in either position. A bridge member 26 of the tumbler frame extends across the frame below the wards to steady the key bit against the wards, the bridge member being 90 preferably made to fit the shank of the key, and the key bit correspondingly cut away to the shank to fit the bridge.

The bolt terminates inwardly in the projections 28 extending rearwardly at its top and bottom. Opposite the bolt end is a bolt stop 27 mounted for vertical movement in a channel member 33 secured in the casing as by the screws 34 the vertical dimension of the bolt stop being such as to just clear the bolt extensions 28 when properly positioned. A 105 lever 29 is pivoted by the screw 30 in a cut away portion of the tumbler frame, and at one end is provided with a head 32 of the curved outline indicated corresponding with a notch in the bolt stop whereby the elevation 110 of the bolt stop may be controlled by the lever. The opposite end of the lever projects into the open portion of the tumbler frame 115 opposite the ward of the first tumbler, and is adapted for movement by a portion of the key bit of proper height to raise the bolt stop to clear the bolt ends 28 as the cam 4 is turned through the earlier portion of its unlocking movement, that is before the cam engages the step 6 of the bolt to move it inwardly.

It will be seen from the foregoing that with the parts as in Fig. 1 the bolt is positively secured in its outer position by the cam, the tumblers and the bolt stop, each of 120

which abut some portion of the bolt to prevent its movement inwardly.

To effect inward movement of the bolt to unlock the door upon which the lock is fitted, the key is first inserted into the key fitting cam aperture described, up to the shoulder formed by the collar 25. During the inserting movement the key is guided by its conical end, which acts as a cam against the balls 15 to release the cam for rotational movement. The key is next rotated clockwise, Fig. 1, during which rotation, the key bit being of proper conformation, the tumblers and the bolt stop are moved into a position to clear the bolt. The bolt however, is prevented from movement until the cam reaches approximately the upward limit of its swing, in other words until the key has been turned 90 degrees to properly position the tumblers and bolt stop; further movement of the cam by the key sliding the bolt to its inner position.

As the bolt reaches its inner position, the key releases the tumblers which under the action of gravity, as soon as the bolt reaches inner position drop to again abut their respective lower bolt projections 17, 17', the bolt projections being now however, inside their respective tumbler ends instead of out-

side as in Fig. 1.

The bolt therefore in inner position is again positively and directly secured; by the cam, which is now in 180 degrees position from that of Fig. 1, and the tumblers; and if the key be now withdrawn, the cam is secured in this position by the detents described, the bolt stop resting upon the lower projection 28 of the bolt.

Thereafter counter-clockwise motion (Fig. 40 1) of the key will return the bolt to outer position, the tumblers being raised by the key as before to clear the bolt projections and thereafter the cam engaging the bolt to move it outwardly, upon completion of which movement the parts again assume their original position.

The cover plate, not shown, may be provided with a closure plate similar to the closure plate 5 and in alignment therewith, and the key bit and tumbler wards be made symmetrical in conformation and arrangement as indicated by the key bit illustrated, in which case the key may be inserted and the lock operated from either side; or, the cover plate may be without any aperture, in which case the key may only be inserted through the closure plate 5, and the key bit and wards may be arranged as desired.

I have preferred to make the closure plate a separate unit, completing the closure plate assembly before securing it in the casing. This is for manufacturing reasons, as well as for the reason that this construction makes the cam locking means inaccessible from without the lock, the closure plate securing

screws being inserted from the inside of the lock as indicated.

What I claim is:

1. In a lock, a casing, a bolt slidable longitudinally therein and having a cam receiving opening, a cam rotatable in said opening to slide said bolt, and having a key bit fitting aperture for rotation by a key, a detent in said casing, means urging said detent to engagement with said cam, said cam having a corresponding radial bore adapted to be engaged by said detent in longitudinal position of said cam to secure said cam in said position, and a detent release in said cam projecting into said aperture and adapted to release said detent when depressed flush with said aperture by a key shank portion. 70 75

2. In a lock, a casing, a bolt slidable longitudinally therein, longitudinal projections extending from the inner end of said bolt, a bolt stop slidable in said casing transversely of bolt movement, to abut either of said projections to prevent inward movement of said bolt, or to clear said projections, and a lever for controlling the position of said bolt stop, said lever being mounted in said casing and provided with a bolt stop engaging portion and a key engaging portion. 80 85 90

3. In a lock, a casing, a bolt slidable longitudinally therein and having an opening, longitudinal projections extending from the top and bottom of the end of said bolt, vertical aligned bolt projections in said bolt opening, a bolt stop vertically slidable in said casing to abut either of said projections to prevent movement of said bolt, or at a certain elevation to clear said projections, a tumbler frame in said opening secured with said casing, tumblers vertically slidable in said frame, said tumblers being adapted to normally abut the lower of said projections to prevent movement of said bolt and having ward portions adapted for engagement with a key bit to raise said tumblers to clear said projections, and a lever for controlling the elevation of said bolt stop said lever being pivotally mounted in said frame and having with a bolt stop engaging portion and a key engaging portion, the key engaging portion of said lever extending below said wards of said tumblers and adapted for key engagement simultaneously therewith whereby co-operation therebetween of a key bit of proper conformation may effect clearance of said bolt stop and tumblers from the path of said bolt. 95 100 105 110 115

4. In a lock, a casing, a bolt slidable longitudinally therein and having a cam receiving opening, a key receiving cam rotatable in said opening to slide said bolt, said cam substantially occupying said opening longitudinally to positively position said bolt, vertically aligned bolt projections in said opening, a tumbler frame in said opening and secured to said casing, tumblers vertically slidable in said frame and adapted to abut the lower of 120 125 130

said projections to prevent movement of said bolt and having wards adapted for engagement by a key bit to raise said tumblers to clear said projections, portions of the cam 5 engaging surface of said bolt opening being of arcuate conformation whereby movement of said bolt may be delayed pending positioning of said tumblers to clear said projections.

5. In a lock, a casing, a bolt slidable longitudinally therein and having an opening, longitudinal projections extending from the top and bottom of the end of the bolt, vertical aligned bolt projections in said opening, a bolt stop vertically slidable in said casing to 10 abut either of said projections to prevent movement of said bolt, or at a certain elevation, to clear said projections, a tumbler frame in said opening secured with said casing, tumblers vertically slidable in said frame, said 15 tumblers being adapted to normally abut the lower of said projections to prevent movement of the bolt and having wards adapted for engagement by a key bit to raise said tumblers to clear said projections and a lever for 20 controlling the elevation of said bolt stop, said lever being pivotally mounted in said frame and having a bolt stop engaging portion and a key engaging portion, the key engaging portion of said lever extending below 25 said tumbler wards and being adapted for key engagement simultaneously therewith whereby co-operation therebetween of a key bit of proper conformation may effect clearance of said bolt stop and tumblers from the path 30 of said bolt, portions of the cam engaging surface of said bolt opening being of arcuate conformation whereby movement of said bolt may be delayed pending positioning of said tumblers to clear said projections.

35 6. In a lock, a tumbler assembly comprising a frame having a central opening and ways in staggered relation on either side thereof, said frame being made up of laminae secured together by means passing therethrough, and 40 tumblers slidable in said ways and each having a ward portion extending into said frame 45 opening.

In testimony whereof I hereby affix my signature.

JOHN T. WHITEHOUSE.
